PERRY PRETTYMAN, OF PARADISE SPRING FARM, OREGON.

Letters Patent No. 87,873, dated March 16, 1869.

IMPROVED RAILWAY-RAIL SPLICE.

The Schedule referred to in these Letters Patent and making part of the same.

To all whom it may concern:

Be it known that I, PERRY PRETTYMAN, of Paradise Spring Farm, in the county of Multnomah, Oregon, have invented a new and useful Improvement in Railroad-Rails; and I do hereby declare that the following is a full, clear, and exact description thereof, which will enable those skilled in the art to make and use the same, reference being had to the accompanying drawings, forming part of this specification.

This invention relates to improvements in railroad-rails, the object of which is to provide rails whereby the cars may be secured against the liability of running off from the track, and to provide more durable rails.

It consists in an improved manner of joining the ends of the rails, and securing them to the ties.

Also, of an improved construction of the rails, whereby the cars, when constructed according to improvements which form the subject of an application by me for Letters Patent, bearing even date herewith, may be securely prevented from running off the track.

Figure 1 represents a side elevation of my improved rails;

Figure 2 represents a plan view of the same; and

Figure 3 represents a transverse section of the same, taken on the line $z z$ of fig. 1.

Similar letters of reference indicate corresponding parts.

I propose to construct my improved rails considerably larger than they are commonly made, and provide the ends with lap-joints, and rivet them together,

as represented in the drawings, where the rail A is provided with a recess in the end, which receives the reduced end of the rail B; and

C represents a rivet, holding the top portions of the rail together, while the bottom portions of the joints are held by the rivets D and by the hook-headed spikes, which are driven down into the recesses F in the base of the rail.

The rivets, or bolts C, are placed on the outer side of the head of the rail, and the head is extended inward for a considerable distance beyond the vertical web G, as represented at H, fig. 3, in order to afford a means for preventing the cars from running off the track, when they are so constructed as to carry auxiliary wheels, suspended from the trucks, so as to project into the space between the said extension H and the base of the rail.

I claim as new, and desire to secure by Letters Patent—

The rails A, B, constructed as described, one, A, being provided with a recess, and adapted to receive the reduced end of the other, B, both being secured together by the vertical bolts C, passing through their upper portions, as herein described, for the purpose specified.

The above specification of my invention signed by me, this 13th day of October, 1868.

PERRY PRETTYMAN.
